VOLTAGE TRANSFORMATION APPARATUS

Raymond H. Sullivan, Rochester, N. Y., assignor
to General Motors Corporation, Detroit, Mich.,
a corporation of Delaware

Application July 24, 1937, Serial No. 155,496

7 Claims. (Cl. 171—97)

This invention relates to voltage transformation apparatus, and more particularly to such apparatus which includes an electromagnetically actuated vibratory reed.

- 5 An object of this invention is to provide an improved means for actuating a vibratory reed, which means is particularly adapted for actuating such a reed in voltage transformation apparatus.
- 10 Another object of this invention is to provide means for actuating a vibratory current switching member in voltage transformation apparatus which means starts this switching member without appreciable delay in attaining full amplitude
- 15 of the vibratory member.
- Another object of this invention is to provide an actuating system for a vibratory current switching device which tends to reduce contact damage due to sparking.
- 20 The above objects are accomplished in a system incorporating a vibratory reed anchored at one end and having its other end free to vibrate by utilizing a set of normally closed contacts, a set of normally open contacts, both of which
- 25 sets of contacts are controlled by the reed, and providing electromagnetic means including two electromagnet windings for actuating the reed, one of which windings is connected to a source of direct current through the normally closed
- 30 contacts and the other of which windings is connected across the normally open contacts, the current flow through the normally closed contacts being interrupted thereby before the normally open contacts short circuit the other windings.

Further objects and advantages of the present invention will be apparent from the following description, reference being had to the accompanying drawing wherein a preferred embodiment of the present invention is clearly shown.

In the drawing:

The single figure of the drawing is a schematic circuit diagram of a system embodying a preferred form of the present invention.

- 45 With particular reference to the drawing, a resilient reed 10 is anchored at one end, such as at 12, and has its other end free to vibrate. Contacts 14 and 16 are mounted on opposite sides of the reed near the free end thereof. Co-
50 operating stationary contacts 18 and 20 are mounted in alignment for engagement with the contacts 14 and 16 respectively. In the normal position of rest of the reed 10, the contacts 14 and 18 and 16 and 20 are disengaged or open.
- 55 Also near the free end of the reed, a contact 22

is mounted on the same side of the reed as the contact 14 and on the opposite side of the reed from the contact 16. A stationary cooperating contact 24 is mounted in alignment for engagement with the contact 22, and these contacts 22 and 24 are engaged or closed when the reed 10 is in the normal position of rest. An electromagnet or electromagnetic means 26 has two windings 28 and 30, which windings are preferably wound in bifilar relation on a common core which is 10 indicated at 32. The core 32 is eccentric to the reed 10 and in magnetic relation thereto.

A battery or source of direct current 34 has one end connected to the reed 10 and its other end connected through a switch 36 to a center 15 tap 38 of a primary winding 40 of a transformer 42. One end of the primary winding 40 is connected to the contact 20, and the other end of the winding 40 is connected to the contact 18. The electromagnet winding 30 is connected across 20 the contacts 16 and 20. The other electromagnet winding 28 has one end connected to the battery 34 through the switch 36 and its other end connected to the contact 24. The resistance of each of the electromagnet windings is preferably high 25 in comparison to the resistance of the halves of the transformer primary winding; as for example, about 30 ohms has been found to be a satisfactory resistance for each of the electromagnet windings as compared to about .06 ohm for each 30 half of the primary winding.

The transformer 42 has a core 44 and a secondary winding 46 which is magnetically coupled to the primary winding 40 through the core 44. The secondary winding 46 preferably has a 35 center tap 48 that is connected to an output lead 50 and is preferably grounded at 52. The ends of the secondary winding 46 are connected to plates or anodes 54 and 56 of a conventional rectifier tube 58 and to the terminals of a condenser 40 49. A filament or heater element 60 of the rectifier tube 58 is connected across the battery 34, and a switch 62 is preferably included in one of the leads from the battery 34 to the filament or heater element 60 to effect deenergization of the 45 filament or heater. A cathode element 64 of the rectifier tube 58 is connected to an output lead 66. A choke coil 68, preferably having an iron core 70, is connected in series with the output lead 66. Condensers 72 and 74 are connected 50 across the output leads 50 and 66 on opposite sides of the choke coil 68. The output circuit including the rectifier tube 58, choke coil 68 and condensers 72 and 74 are merely illustrative of one kind of an output circuit that may be used 55

in the present system. It is, of course, understood that by utilizing additional contacts the rectification of the secondary voltage could very well be accomplished through the action of the 5 reed and without the rectifier tube 58. It is also understood that the present invention might very well be embodied in a system which does not include a rectifying means, or one which uses any one of the number of varieties of filters with 10 the rectifying means.

In the operation of the system disclosed, the vibratory reed 10 has a normal position of rest, such as that illustrated in the drawing, in which the contacts 14 and 18 are open, the contacts 16 15 and 20 are open and the contacts 22 and 24 are closed. Upon closing the switch 36, the electromagnet winding 28 is energized by current from the battery or source of direct current 34 through the normally closed contacts 22 and 24. Also, the 20 electromagnet winding 30 is energized by current from the battery or source of direct current 34 which flows through one half of the primary winding 40. The consequent energization of both 25 windings of the electromagnet provides a strong attracting force which moves the free end of resilient reed 10 toward the core 32. At a pre-determined point in the movement of the reed 10 toward the core 32 at the contacts 22 and 24 open to effect deenergization of the electromagnet 30 winding 28. Continued movement of the reed 10 toward the core 32 effects engagement of the contacts 16 and 20. The engagement of the contacts 16 and 20 short circuits the electromagnet winding 30 to effect deenergization thereof, al- 35 though the short circuiting of the electromagnet winding 30 tends to delay the decay of the flux of the electromagnet while the contacts 16 and 20 are engaged. The deenergization of both of the electromagnet windings 28 and 30 releases 40 the reed 10, so that the resilience thereof carries the free end of the reed away from the core 32, whereupon the contacts 22 and 24 reengage, and thereafter the contacts 14 and 18 engage. Either one or the other of the contacts 22 and 24 are 45 resiliently mounted so as to permit the reed 10 to swing to the left from the position shown in the drawing in order to bring the contact 14 into engagement with the contact 18 after contact 22 has engaged contact 24. During the engagement of 50 the contacts 14 and 18, the reed is stressed in a position away from the core 32, and due to such stress, as well as the reenergization of the electromagnet windings 28 and 30, the above outlined action of the reed is repeated.

55 During the time that the contacts 16 and 20 are closed, one half of the primary winding 40 is energized by current flow from the battery or source of direct current 34 through those contacts. During the time that the contacts 14 and 60 18 are closed, the other half of the primary winding 40 is energized by current flow from the battery or source of direct current 34 through those contacts, and by a current flowing in the opposite direction in the primary winding from 65 that which energized the first mentioned half thereof. The alternate energization of the halves of the primary winding 40 in opposite directions during vibratory movement of the reed 10 creates a full wave alternating potential across the 70 secondary winding 46, which secondary voltage value depends upon the characteristics of the transformer 42. The resistance of the electromagnet winding 30 is preferably sufficiently high that the current flow through the half of the 75 primary winding that is in series therewith when

the contacts 16 and 20 are open is small with respect to the current flow therethrough when those contacts are closed.

From the foregoing description, it will be readily understood that when the reed is stationary, and then the electromagnet windings 28 and 30 are energized by closing the switch 36, the pull or force of the electromagnet 28 on the reed 10 is strong. This strong pull or force is very desirable in starting the reed, to 5 effect quick starting, without the delay of several cycles of reed movement before the reed reaches full amplitude. It is also desirable to have such strong pull when the reed is away from the core 32 and during operation, so that the reed will 10 vibrate uniformly and properly over a wide range of voltages from the source 34, and particularly 15 when the voltage of the source 34 is below normal. It has been found that the delay of the decay of the electromagnet flux resulting from 20 the short circuiting of the electromagnet winding 30 has a very beneficial effect in the reduction 25 of contact sparking. It will also be understood that the relation, spacing and adjustment of the various contacts in the instant system provides a 30 flexibility of design which permits desirable operation of the reed to be attained. When the contacts are properly adjusted, so that they make and break in the order defined above, practically 35 sparkless operation of the contacts results. The 40 present system therefore prolongs contact life by minimizing sparking at the contacts, as well as by limiting mechanical wear or damage to the contacts; and the system accomplishes these results together with providing a device which 45 starts and reaches full amplitude very quickly, and operates satisfactorily over a wide range of voltage.

While the embodiment of the present invention as herein disclosed, constitutes a preferred 40 form, it is to be understood that other forms might be adopted, all coming within the scope of the claims which follow.

What is claimed is as follows:

1. In voltage transformation apparatus, the 45 combination comprising, a resilient vibratory reed anchored at one end and having a plurality of contacts mounted thereon near the other end; a plurality of cooperating contacts adapted to engage the contacts on the reed, one pair of said 50 contacts being normally engaged and others of said contacts being normally open; a battery; a transformer having a primary winding, said normally open contacts controlling the current flow from the battery to the primary winding; and an 55 electromagnet having a pair of windings for effecting vibratory movement of the reed, one of the electromagnet windings being connected to the battery through the normally closed contacts, and the other of the electromagnet windings 60 being connected across a pair of the normally open contacts.

2. In voltage transformation apparatus, the 65 combination comprehending, a resilient reed anchored at one end and having its other end free to vibrate; means including a pair of electromagnet windings for effecting vibratory movement of the reed; a transformer; a battery; stationary contacts and movable contacts comprising cooperating pairs, of engageable contacts adapted to 70 intermittently engage during vibratory movement of the reed, at least one pair of said contacts controlling current flow from the battery to the transformer, one of said electromagnet windings 75 being connected across a pair of said contacts,

and the other electromagnet winding being connected to the battery through one of the pairs of contacts.

3. In voltage transformation apparatus, the combination comprehending, a resilient reed anchored at one end and having its other end free to vibrate means including a pair of electromagnet windings for effecting vibratory movement of the reed; a transformer having a primary winding; a source of direct current; stationary contacts and movable contacts comprising cooperating pairs of engageable contacts adapted to intermittently engage during vibratory movement of the reed, a pair of said contacts controlling current flow from the source of direct current to the primary windings, one of said electromagnet windings being connected across the last mentioned pair of contacts, the other of said electromagnet windings being connected to the source of direct current through another of said pairs of contacts, the last mentioned pair of contacts being normally engaged.

4. In voltage transformation apparatus, the combination comprehending, a resilient reed anchored at one end and having its other end free to vibrate; means including a pair of electromagnet windings for effecting vibratory movement of the reed; a transformer having a primary winding having portions connected to a center tap; a source of direct current; stationary contacts and movable contacts comprising cooperating pairs of engageable contacts adapted to intermittently engage during vibratory movement of the reed, two of said pairs of contacts alternately effecting current flow through said portions of the primary winding, the last mentioned pairs of contacts being normally open, one of the electromagnet windings being connected across one of the last mentioned pairs of contacts, and the other electromagnet winding being connected to the source of direct current through another of said pairs of contacts, the last mentioned pair of contacts being normally closed.

5. In voltage transformation apparatus, the combination comprehending, a resilient reed anchored at one end and having its other end free to vibrate; a pair of normally closed contacts, a

pair of normally open contacts, one of the contacts of each of said pairs being mounted on the reed; a battery; electromagnetic means for actuating the reed including two electromagnet windings; one of the windings being connected to the battery through the normally closed contacts, and the other winding being connected across the normally open contacts.

6. In voltage transformation apparatus, the combination comprehending, a resilient reed anchored at one end and having its other end free to vibrate; a pair of normally closed contacts, a pair of normally open contacts, one of the contacts of each of said pairs being mounted on the reed; a battery; electromagnetic means for actuating the reed including two electromagnet windings; one of the windings being connected to the battery through the normally closed contacts, and the other winding being connected across the normally open contacts, said contacts and reed being so arranged that movement of the reed in one direction effects breaking of the normally closed contacts before the normally open contacts engage.

7. In voltage transformation apparatus, the combination comprehending, a resilient reed anchored at one end and having its other end free to vibrate a pair of normally closed contacts, two pairs of normally open contacts, said pairs of normally open contacts being on opposite sides of the reed; a source of direct current; a transformer having a center tapped primary so connected that the halves of the primary are alternately energized from the source of direct current; an electromagnet for effecting vibratory movement of the reed, said electromagnet having a plurality of windings thereon, one of the electromagnet windings being connected to the source of direct current through the normally closed contacts, and another of the electromagnet windings being connected across one pair of normally open contacts, said contacts being so arranged that the last mentioned one pair of normally open contacts short circuits the electromagnet winding that is connected thereto after the normally closed contacts open.
